UNITED STATES PATENT OFFICE.

OMER J. RHODES, OF GALVESTON, TEXAS.

DESIGN FOR A LANTERN-BOX.

SPECIFICATION forming part of Design No. 31,744, dated October 31, 1899.

Application filed October 7, 1899. Serial No. 732,966. Term of patent 14 years.

To all whom it may concern:

Be it known that I, OMER J. RHODES, a citizen of the United States, residing at Galveston, in the county of Galveston and State of Texas, have invented a certain new and useful Design for Lantern-Boxes, of which the following is a specification.

My invention is a design for lantern-boxes or light-boxes for children's use; and it consists of the shape and configuration illustrated in the accompanying drawing and hereinafter described.

The box consists of a bottom 1 and top 2, having their ends inclined oppositely to form points 3, sides 4 and 5 connecting the top and bottom, and inclined end panels 6 and 7 connecting the oppositely-inclined ends of

the top and bottom of the box. The sides 4 and 5 and inclined end panels 6 and 7 are formed with openings 8, representing windows, and at the junction of the two end panels 6 is an ornamental projection 9, in form of a bird's head.

The top 2 of the box is formed with a central opening 10.

I claim—

The design for a lantern-box herein shown and described.

In testimony whereof I affix my signature in presence of two witnesses.

OMER J. RHODES.
